UNITED STATES PATENT OFFICE.

ROBERT O. THOMPSON, OF CAMPBELL HALL, NEW YORK.

RAILWAY.

1,359,205.

Specification of Letters Patent. Patented Nov. 16, 1920.

Application filed April 9, 1919. Serial No. 288,826.

To all whom it may concern:

Be it known that I, ROBERT O. THOMPSON, a citizen of the United States, residing in Campbell Hall, in the county of Orange and 5 State of New York, have invented certain new and useful Improvements in Railways, of which the following is a specification.

My invention relates to an improvement in railways comprising rails that are non-10 creeping and endless in effect, held against movement with respect to the sleepers or cross-ties, but at the same time left free to contract or expand in response to a fall or rise in temperature due to changes in the 15 weather or in the seasons of the year.

An object of my invention is to provide a railway in which the rails making up the track are shaped and united in such fashion that any up and down movement of the ends 20 of the rails, when rolling stock is passing over the same, is prevented, and thereby all pounding of the ends of the rails upon the cross-ties is avoided; and in which the rails are braced laterally to counteract the effect 25 of forces tending to distort the track, and engaged at points between their ends so that the possibility of any longitudinal movement of the rails, such as shifting or creeping of the same, is entirely obviated.

An important feature of my invention is 30 a rail-seat of special design, which is secured to the cross-ties at both the middle and the ends of the rails, and which serves both to strengthen the rails and keep them in proper 35 position; the seats at the ends of the rails being adapted to hold the rails against movement sidewise and those at the middle of the rails acting to hold the rails against movement in a lateral direction and longitudinal movement likewise; all the seats 40 further acting to prevent tilting of the rails when an outward thrust is exerted upon the latter.

Other objects and advantages of my invention will appear from the following description taken in connection with the accompanying drawings which illustrate the best embodiment of my invention now known to me. This disclosure, however, is 45 explanatory only, and I may of course resort to changes in what is actually shown, within the scope and spirit of my invention as the same is defined by the general meanings of the terms in which the appended 50 claims are expressed.

On the drawings:

Figure 1 shows in the plan a portion of a railway according to my invention;

Fig. 2 is a perspective view of a seat for 60 engaging the rails thereof;

Fig. 3 is a sectional view through one of the rails, illustrating the manner in which one rail is connected to another to provide a joint between them;

Fig. 4 is a perspective view showing how 65 the rails are shaped at their ends;

Fig. 5 is a view of the inner faces of a fish-plate employed in the joints for the rails in my invention;

Fig. 6 is a top plan of the same; 70

Fig. 7 is a top plan of a companion fish-plate of slightly modified construction;

Fig. 8 is a side view of the rails at the 75 joints between them;

Fig. 9 is a side view of an element for preventing the loosening of the bolts in the 80 joints between the rails; and

Fig. 10 is a top plan of a portion of one of the rails showing how the same are shaped adjacent the middle of the same so as to be 85 engaged by the rail-seats and held against longitudinal as well as lateral movement.

The same numerals identify the same parts throughout.

Referring particularly to the drawings, I 85 employ the numeral 1 to indicate sleepers or cross-ties which support rails 2. These rails may be of any standard weight and length; and, as shown in Fig. 1, the ties which support these rails are connected in 90 threes at the middle and ends of the same by a special rail-seat upon which the middle and ends of the rails rest. Only the ties at the middle and ends of the rails appear in Fig. 1; those between the ends and middle 95 of the rails being omitted, for the sake of clearness. Each rail comprises a base 3, a web 4 and a ball 5; and, as shown particularly in Fig. 4, the faces of the ends of the rails which extend over the bases 3 and 100 webs 4, are perpendicular to the lengths of the rails, while the terminal faces of the balls or tops 5 are inclined with respect to the length of the rails. In other words, the rails are cut off squarely at their ends over 105 the bases and webs, while the ends of the tops are beveled. Therefore, when the rails are laid end to end on the ties, the web 4 of one rail will provide a corner at one end 110 which projects in front of the beveled end

at the top, and may extend under the beveled end of the top of the adjacent rail; thereby helping to support the adjacent rail when the weight of a car or locomotive 5 comes upon the same. By shaping the ends of the rails in this way, a vehicle running along the track will apply its weight to the ends of the successive rails gradually; reaching one rail before it entirely leaves the last 10 one. For example, the wheels of a train traveling from left to right in Fig. 1, will engage the pointed extremities at the tops of the middle rails before leaving the pointed extremities at the tops of the rails shown 15 in part at the left; and because of this gradual transfer of weight from one rail to the other, the ends of the rails are not subjected suddenly to any great downward acting force; as in the case of rails having their 20 ends cut off squarely from ball to base; and, consequently, the pounding of the ends of the rails upon the cross-ties is entirely eliminated. The corner of the web 4, shown in Fig. 4, as projecting beyond the lower edge 25 of the beveled face of the top 5, helps materially to afford this result, because it enables the end of one rail to afford some support to the end of the other, regardless of the direction in which a train may be traveling, as 30 soon as a wheel comes into such position as to engage portions of the ends of two adjacent rails simultaneously. I also wish to call attention here to the fact that the ends of the bases 3 and webs 4 being perpendicular to the longitudinal axes of the rails, will enable the rails to be properly aligned and connected together; and no displacement or getting out of alignment of the rails, which might otherwise occur as a result of the 35 inclined or beveled faces of the tops 5 of the rails, can take place.

As shown in Fig. 1, the lateral edges of the bases 3 of the rails, are continuous and uninterrupted at the ends of the rails; while 40 the lateral edges of the bases 3 at the middle of the rails, are provided with notches 6, for the purpose of enabling the rails to be engaged and held against longitudinal movement by the seats disposed upon the ends of the ties 1. Each of these seats, as shown in Fig. 2, comprises a body 7, to be mounted upon the ends of three adjacent ties; which are preferably to be secured together at their 45 opposite ends by means of bands or strips 8. These bands or strips 8 make the three ties at the ends of the rails and at the middle of the same, fast with one another; giving in effect a single tie at the points mentioned. Each seat comprises transverse portions 9 50 resting upon the ends of the ties, and portions 10 connecting the portions 9. Each portion 9 is provided with projections 11 bent downward against the sides of the ties; these projections having openings through 55 which nails or spikes can be driven to hold

the seat and ties together. The opposite edges of the connecting portions 10 between the portions 9, are bent upward providing flanges 12; and the ends of the portions 9 which are to be located adjacent the bands 60 8, are provided with extensions 13 which are bent over and upward, and which have their edges turned to provide strengthening ribs 14. In addition to the spikes driven through the projections 11, I may also drive 65 spikes into the ties through openings 15 in the opposite ends of the portions 9. One of these seats will be at the middle of each rail, and one at the end of the same; each rail resting upon the entire seat disposed at the 70 middle thereof, and upon half the seat disposed at the extremity of the same, as indicated in Fig. 1.

When the rails are in position upon the ties, and the seats therefor are secured to 75 the ends of the ties at the middle and ends of the rails, the rails and their seats will be in such relation that the bases of the rails will extend across the portions 9 and along the connecting portions 10 from the 80 end of each seat to the other; with the extensions 13 on the outside of the rails and engaging the same along the lower faces of the balls or tops of the rails 2. These extensions 13 thus constitute braces which 85 have the effect of strengthening the rail laterally; preventing spreading and other distortion, and they are especially useful upon curves where the outer rail receives most of the thrust of the train wheels. The seats at 90 the middle of each of the rails engage the notches or indentations 6 thereof, by reason of the presence of the projections 12, and thus hold the rail against any longitudinal movement. At the ends of the rails, the 95 seats will have similar projections between which the bases 3 of the rails will be located; but the bases 3 of the rails will not be provided with any notches or indentations 6 at the ends of the rails, as already 100 stated. These projections 12 secure the rails against any movement toward each other, and coöperate with the braces 13 to hold the rails against any movement away from 105 each other or spreading apart; while the 110 projections 12 at the middle of each rail have the additional function of preventing the lengthwise movement of the rail, but do not interfere with the usual expansion or contraction of the rail upon changes in temperature. By the absence of indentations 6 in the bases 3 at the ends of the rail, these 115 expansions and contractions due to temperature changes, are allowed to take place freely; but they can only manifest themselves in slight movements of the rail ends shrinking apart. Under such conditions the rail ends can slide to the required extent along 120 the seats beneath them, but each rail re- 125 130

5 mains anchored securely in the middle. Of course I may use in connection with my railway, the spikes ordinarily employed to fasten the bases of the rails to the cross-ties; putting these spikes wherever needed in the ties between the seats or even driving them through the seats also if desired.

To unite the ends of the rails, I employ a fish-plate 16 having recesses 17 into which 10 I insert anti-frictional elements, such as rollers 18. The recesses are preferably provided by boring into the fish-plate at its lateral edges; the recesses extending not quite through from one edge to the other, 15 and being of such design that they expose a portion of rollers 18, as shown in Figs. 6 and 7, projecting slightly beyond the inner face of the plate. As will be understood these rollers can be slipped into the recesses 20 17 lengthwise, but cannot be removed side- wise therefrom. Two fish-plates are em- ployed, each having recesses 17 with rollers 18, and one having smooth holes 19; the other having bolt holes which are threaded 25 as shown at 20. The fish-plates are at- tached as shown in Figs. 3 and 8, bolts 21 being employed to make these fish-plates grip to the webs of two adjacent rails be- 30 tween them with the rollers 18 in contact with the opposite faces of the webs 4. These bolts will be threaded at one end and have heads 22 at the other; but between the threaded ends and the heads they are smooth to pass freely through the openings 19 in 35 one plate, and take hold of the threads in the openings 20 in the other. By this con- struction, the use of the nuts is dispensed with and I am enabled to unite the rails by means of a shorter bolt. The holes through 40 the webs 4 are elongated as shown in Fig. 4 at 23, and the bolts 21 are held against becoming loose or turning backward by means of a locking element or plate 24 hav- 45 ing openings 25. Each of these openings is in the form of an eight pointed star, and the plate is applied by fitting it over the heads of the bolts 21. Of course the bolts can always be turned in such position that the plate 24 can be fitted against the adja- 50 cent fish-plate 16 and engage the heads 22 of all of the bolts. It is held in place by drilling holes through the heads 22 of not more than two of the bolts and applying re- taining elements such as cotter pins 26.

55 The seats at the middle of the rails will be the same as the seats at the ends of the rails; except that the projections 12 of the seats being placed at the middle of the rails, will be closer together to enter the indentations 6; while the projections 12 of the seats for the ends of the rails must be at least as far apart as the width of the bases 3. As will be understood, these seats can be made by stamping and bending them out of a 60 single piece of metal.

From the foregoing description it will be clear that my improved railway is very ef- ficient and durable yet simple and relatively inexpensive; and well adapted to attain the ends and purposes of my invention.

70

As indicated in Figs. 1 and 2, the seats for the rails have the projections 12 to be dis- posed along the inner edges of the bases of the rails bent somewhat toward the portions 10 so as to extend over the adjacent edges of 75 the bases 3 of the rails, both at the middle of each rail where these projections enter the indentations 6, and at the ends of the rails where there are no such indentations. Hence the projections 12 along the inner 80 edges of the bases of the rails, coöperate with the extensions 13 along the outside of the rails, to prevent the rails from being tilted or upset when the flange of the wheel of a car or locomotive exerts a thrust against 85 the side of the tops of the rails in an out- ward direction, as is the case when a curve is encountered or when the rolling stock sways from side to side on either a curved or 90 straight track.

I also wish to call attention to the fact that the lower faces of the tops 5 of each rail on both sides of the web 4, are made flat over a given width; so are portions of the bases 3 along the web 4 directly below the 95 flat under faces of the tops 5. The fish-plates 16 rest upon the flat horizontal por- tions of the bases 3 along their lower edges, and the tops of the fish-plates engage the flat under faces of the tops 5 of the rails. 100 Hence, the fish-plates not only unite the ends of the rails, but also strengthen and sup- port the points of the beveled ends of the tops 5; especially along the inside of the rails, where the weight of the rolling stock 105 is most felt. Along the outside of the rails the fish-plates 16 may be beveled slightly along their outer edges or recessed thereat to enable the projections 13 to engage the un- der faces of the tops 5 as best shown in 110 Fig. 3.

While I have shown the bands 8 as con- necting the ends of three ties, I may obvi- 115 ously unite the ends of more than three ties by this band if circumstances require, when the rail-seats are to be placed into position. I may also make these rail-seats so as to en- gage the tops of more than three rails at the ends or even less than three rails, if necessary.

120 Preferably, there is to be a roller 18 adja- cent each of the bolts 21 so that no matter how tight the bolts are turned, the surface of the fish-plates will not lie directly in con- tact with the webs 4.

The projections 11 are of great value in secur- 125 ing the rail-seats to the ties; and any fastening device which is driven through open- 130 ings in these projections, remains firmly em- bedded in the tie in spite of any force ex-

erted on the rails to displace the latter. Obviously such force will act not in a direction to withdraw or loosen such fastening devices, but transversely of the same. These 5 fastening devices will therefore, hold very efficiently, and will also, by their engagement with the rail-seats, enable the spikes or fastening devices which are driven into the ties vertically, whether through the rail- 10 seats or elsewhere, to resist pulling out to the greatest advantage.

The herein described railway is, therefore, not only non-creeping in character, but also the rails thereof are continuous and 15 endless in effect, although capable of expanding and contracting as much as necessary.

As will be understood, the rollers 18 allow the expansion and contraction of the rails 20 by keeping the fish-plates from binding upon the webs, and yet enable the bolts to hold the plates and the rails tightly enough to make efficient joints.

The rails are assembled with the seats 25 either by sliding the seats on the bottoms of the rails by endwise movement and then fastening the seats to the ties; or the projections 12 which engage the inner edges of the bases of the rails may be shaped to allow 30 the rails to be set down on the seats against the extensions 13, and these projections bent upward and over to secure the rail and seat together. Any other feasible and convenient way of assembling the rails and seats may be 35 followed if desired.

Having described my invention, what I believe to be new and desire to secure and protect by Letters Patent of the United States is:

40 1. A seat for a rail comprising portions to rest upon and to be secured to cross-ties for the rail, and portions for connecting the first named portions, the first named portions having braces for engaging the outside of the rail adjacent the top of the same, the connecting portions having projections along their opposite edges for engaging both sides of the base of the rail.

2. A railway comprising cross-ties, rails 50 thereon; bands for uniting the ends of a plurality of said cross-ties at the ends and middle of the rails; seats resting upon and secured to the ends of cross-ties at the middle and the ends of said rails; the seats 55 at the middle of the rails having projections engaging indentations in the bases of the rails; the seats at the ends of the rails having projections in each of the edges of the bases thereof; all of said seats having 60 braces engaging the outside of the rails under the tops thereof, the tops of said rails being beveled at the ends; fish-plates for uniting said ends, said fish-plates carrying anti-frictional elements to engage the 65 rails; bolts for causing the fish-plates to

grip the rails, said rails having elongated openings to give passage to the bolts; and a member for locking said bolts.

3. A railway comprising cross-ties, rails thereon; seats to rest upon said cross-ties 70 at the middle and ends of said rails, each of said seats comprising portions to be secured to the cross-ties and portions for connecting the first named portions, the first named portions having braces for engaging the outside of the rails adjacent the top of the same and the connecting portions having projections along their opposite edges for engaging both sides of the bases of the rails.

4. A railway comprising cross-ties, rails thereon; and seats for the middle and ends of said rails, each seat comprising portions to rest upon and be secured to the cross-ties and portions for connecting the first named 85 portions, the first named portions of all seats having braces for engaging the outside of the rails adjacent the tops of the same, while the connecting portions of the seats at the middle of the rails have projections to engage indentations in the bases of the rails to hold the rails against lateral and longitudinal movement, and the connecting portions of the seats at the ends of the rails have projections to engage the edges 90 of the bases of the rails to hold said rails against lateral movement but permitting the ends of the rails to move thereon, as the rails expand and contract.

5. A seat for a rail comprising portions 100 to rest upon and be secured to cross-ties for the rail, said portions having downward-extending projections to be fastened to the sides of said ties, and portions for connecting the first-named portions, the first-named portions also having braces for engaging the outside of the rail adjacent the top of the same, the connecting portions having projections along their opposite edges for engaging both sides of the base of the rail.

6. A railway comprising cross-ties, rails thereon, seats to rest upon said cross-ties at the middle and ends of said rails, each of said seats comprising portions to be secured to the cross-ties and portions for connecting the first-named portions, the first-named portions having downward-extending 115 projections to be fastened to the sides of the ties, and having braces for engaging the outside of the rails adjacent the tops of the same, and the connecting portions having projections along their opposite edges for engaging both sides of the bases of the rails.

7. A railway comprising cross-ties, rails 125 thereon, and seats for the middle and ends of said rails, each seat comprising portions to rest upon and be secured to the cross-ties, and portions for connecting the first-named portions, the first-named portions 130

of all seats having downward-extending projections to be fastened to the sides of the ties and having braces for engaging the outside of the rails adjacent the tops of the same, while the connecting portions of the seats at the middle of the rails have projections to engage indentations in the bases of the rails to hold the rails against lateral and longitudinal movement, and the connecting portions of the seats at the ends of

the rails having projections to engage the bases of the rails to hold said rails against lateral movement but permitting the ends of the rails to move thereon as the rails expand and contract.

15

In witness whereof I have signed my name to this specification this 29th day of March, 1919.

ROBT. O. THOMPSON.
